US00D733199S

(12) **United States Design Patent**
Kimmel et al.

(10) **Patent No.:** **US D733,199 S**
(45) **Date of Patent:** **** Jun. 30, 2015**

(54) **LIQUID FUEL TORCH BURNER WITH
INDENTED TOP**

(71) Applicant: **LAMPLIGHT FARMS
INCORPORATED**, Menomonee Falls,
WI (US)

(72) Inventors: **Adam S. Kimmel**, Union Grove, WI
(US); **Ron White**, North Prairie, WI
(US); **Richard Catalano**, Hartland, WI
(US)

(73) Assignee: **Lamplight Farms Incorporated**,
Menomonee Falls, WI (US)

(**) Term: **14 Years**

(21) Appl. No.: **29/475,917**

(22) Filed: **Dec. 9, 2013**

(51) LOC (10) Cl. **15-09**

(52) U.S. Cl.

USPC **D15/144; D26/8**

(58) **Field of Classification Search**

USPC D26/8, 16, 116, 128; D15/144, 144.1,
D15/144.2

(57) **CLAIM**

The ornamental design for a liquid fuel torch burner with indented top, as shown and described.

DESCRIPTION

FIG. 1 is a perspective view of the torch burner of the present disclosure.

FIG. 2 is a level side view of the torch burner of the present disclosure.

FIG. 3 is a level side view of the torch burner of the present disclosure opposite the view of FIG. 2.

FIG. 4 is a level side view of the torch burner of the present disclosure rotated ninety degrees to the left from the view of FIG. 2.

FIG. 5 is a level side view of the torch burner of the present disclosure opposite the view of FIG. 4.

FIG. 6 is a superior view of the torch burner of the present disclosure.

FIG. 7 is an inferior view of the torch burner of the present disclosure; and,

FIG. 8 is an inferior perspective view the torch burner of the present disclosure.

The broken lines in the Figures are for the purpose of illustrating the environment in which the design is associated and form no part of the claimed design.

1 Claim, 6 Drawing Sheets
